UNITED STATES PATENT OFFICE.

WALThER NERNST, OF GÖTTINGEN, GERMANY, ASSIGNOR TO GEORGE WESTINGHOUSE, OF PITTSBURG, PENNSYLVANIA.

ELECTRIC GLOW-LAMP.

SPECIFICATION forming part of Letters Patent No. 685,727, dated October 29, 1901.

Original application filed April 28, 1898, Serial No. 679,081; Divided and application filed May 29, 1899, Serial No. 718,624;

Again divided and this application filed April 10, 1901. Serial No. 55,221. (No model.)

To all whom it may concern:

Be it known that I, WALThER NERNST, a subject of the Emperor of Germany, and a resident of Göttingen, Germany, have invented certain new and useful Improvements in Electric Glow-Lamps, (division of an application filed by me April 28, 1898, Serial No. 679,081,) of which the following is a specification.

10 My invention relates in a general way to the class of devices known as "incandescent electric lamps" and a method of lighting; but it differs fundamentally from the incandescent lamps and methods heretofore used and involves certain peculiar features and characteristics which justify its classification as a distinct and novel species.

Heretofore all practical incandescent electric lamps have comprised a filament of conducting material, usually, if not always, of carbon, contained within an inclosing chamber from which the air is exhausted. The fact that the filaments heretofore employed will oxidize when heated in the open air has necessitated inclosing them in vacuum-chambers.

Various refractory materials comprising certain oxids, sulfids, silicates, and other salt-like compositions of metals are specially qualified to emit light when heated to a high temperature. It has been proposed to utilize the light-emitting qualities of such materials by maintaining them in a state of incandescence by a gas-flame—as illustrated by the well-known "Welsbach burner," for instance. When the light-emitting qualities of these refractory materials were to be used in connection with electric lighting at ordinary voltages, it has heretofore been considered necessary to either maintain them in an incandescent state by placing them in proximity to conductors heated by electric currents or to coat them or add to them or in some way combine with them some good conducting material, such as a metal or carbon, which should afford a conducting-path for the current. For example, it has been proposed to impregnate or coat conductors—such, for instance, as platinum, iridium, or carbon—with a refrac-

tory material—such, for instance, as calcium or zirconia—and to use the heat developed in the conducting material for maintaining the refractory material in an incandescent light-emitting condition. Such combinations, however, have been found to be inoperative for any useful purpose. The platinum or carbon or other conducting material either itself melts or disintegrates or causes the refractory material to crack off or disintegrate.

I have discovered that certain refractory salt-like combinations, particularly oxids usually classed as the "rare earths," which are at ordinary temperatures "non-conductors of electricity," as that term is usually employed, will when raised to the high temperature of incandescence become sufficiently good conductors to permit the passage of an electric current under moderate differences of potential and may be maintained sufficiently heated to retain their thus-acquired conducting qualities by the passage of the electric current therethrough. These materials when so traversed by electric currents not only emit more light under the influence of a given amount of electrical energy than the ordinary incandescent lamp, but they also resist decomposition and disintegration even in the open air, and therefore a lamp constructed in accordance with my invention does not require a vacuum-chamber, though a vacuum-chamber may be used in certain cases, if desired.

The general characteristics of the light-giving portion of my lamp are so widely different from those of the ordinary incandescent electric lamp that to term it a "filament" would be not only inappropriate, but to a certain extent misleading. The light is emitted therefrom without combustion or material disintegration even when exposed to the air, and being translucent it emits light from its interior and from its surface, and I have given the name "glower" to the light-giving portion and "glow-lamp" to the lamp itself as being properly applicable.

The materials which I have discovered to possess the qualities above referred to may be classed under the general term of "dry

electrolytes" or "dry conductors" of the second class. By the expression "conductors of the second class" I refer to those which when in a conducting condition conduct current by electrolytic action.

Prominent among the materials with which I have obtained excellent results may be mentioned oxid of magnesium, or magnesia, and oxid of zirconium, or zirconia; also, the oxids 10 of yttrium, cerium, thorium, and the like. These materials when in a dry state and at normal temperatures are practically insulators or non-conductors; but when glowers made from them are heated to a state of in- 15 candescence they acquire conducting qualities to such an extent that electricity may be caused to pass through them at ordinary low pressures in sufficient quantities to keep them in the state of incandescence even after the 20 means employed for imparting the original starting-heat is withdrawn. Instead of using these materials individually or alone for forming the glower two or more of them may be mixed or combined in varying proportions 25 with advantageous results. Glowers made from a proper mixture of certain of the materials will pass into the conducting state at a lower initial or starting temperature than will a glower made from one of the materials 30 alone and will maintain, under the passage of the electric current, a luminous condition without deterioration better and for a longer time than will any single one of such materials. It is not, therefore, the mere mixture 35 of such materials that I prescribe, but the utilization of such mixtures on account of their superior properties when brought to and maintained in a luminous condition. These materials even when in their best op- 40 erating conducting condition have a specific resistance so great with reference to that of carbon that a glower to be used with a given voltage may be much shorter and thicker than the carbon filament of an ordinary incandescent lamp. For instance, a practical 45 glower of, say, one-fiftieth of an inch in diameter and one-half an inch in length may be made which when heated to a low incandescence will become a sufficiently good con- 50 ductor to be traversed under a one-hundred-volt difference of potential by a sufficient current to bring it to and maintain it at a state of high incandescence. A current of, say, four-tenths of an ampere, or thereabout, will 55 accomplish this result. As the material has sufficient strength to enable it to be used in much longer lengths than that above referred to, it is possible to construct lamps adapted to be operated at very much higher voltages than 60 is practicable with lamps using carbon filaments, a feature which may be utilized to obtain economy of transmission. This feature, in connection with the high efficiency of the lamp, renders it possible to secure either a 65 given illumination with a much higher transmission efficiency than at present obtained or a higher illumination with the present

transmission efficiency, or both the illuminating and transmission efficiencies may be materially increased.

There are numerous different proportions in which the different refractory materials adapted to the purposes of my invention may be used, and there is a very wide range for the selection of the different materials to be 70 mixed together, and therefore I will attempt only, and it will only be necessary, to specify one or two examples. Very excellent results have been obtained from a mixture of approximately seventy per cent. of zirconia and 75 thirty per cent. of yttria, (oxid of yttrium.) Another mixture which I have used with 80 good advantage consists of approximately ten per cent. of zirconia, seventy per cent. of thoria, and twenty per cent. of yttria. I have 85 also obtained excellent glowers from a mixture of about seventy per cent. of thoria and thirty per cent. of yttria. Another mixture consists of 0.5 per cent. of ceria, eighty per cent. of thoria, with 19.5 per cent of yttria. 90 These percentages may be widely varied, and, generally speaking, the oxids of the rare 95 earths are well adapted for mixture in widely-varying proportions.

The process of preparing the glowers from which I have heretofore obtained the best results when two or more of the oxids are to be used together consists in thoroughly pulverizing and mixing the materials together into very intimate relations, then mixing there- 100 with a binder of clear-starch paste, making a plastic mass which should be thoroughly worked. The water used in making the paste should be clear and preferably distilled to avoid the presence of lime, which is more 105 volatile than the oxids of the rare earths, and therefore undesirable. The plastic mass may then be inserted in a press adapted to force the mixture through a small hole of the requisite diameter, dependent upon the ultimate 110 diameter desired for the glower, and as the material leaves the press it may be hung over a glass rod or laid upon a suitable supporting- 115 surface and allowed to dry. The material acquires sufficient strength when dried to be 120 conveniently handled, and it is then heated to a very high temperature in any suitable manner—for instance, in an oxyhydrogen flame. It is desirable that as great a specific gravity as possible may be given to the material—that 125 is to say, the smallest diameter for a given mass of a given length. Care should be taken that every part of the glower is brought to a high incandescence. Usually it is advan- 130 tageous to heat the material gradually, so as to drive off the moisture and the binding material slowly, and thus lessen the liability of the surface becoming cracked. For example, it may be passed through a preliminary heat in a porcelain kiln. The eventual heating, 135 however, should be carried to an extremely high temperature. When the material has been thus prepared, a proper length, dependent upon the voltage and current with which it

is to be used, is mounted between two suitable conducting-wires. The ends may advantageously be fastened mechanically in any suitable way—as, for instance, by inserting them into suitable sockets made by forming into spirals the conducting-wires, which may be of platinum or other good conducting materials which melt only at a very high temperature. The junctions of the glower 5 with the respective wires are then built up by placing thereon in a liquid or paste-like condition small quantities of a cementing material and heating and drying the same in a gas-flame or otherwise. This process is repeated until a firm union is obtained between the respective ends of the glower and the wires. It is advantageous also to make the points of juncture with the wires of larger 10 diameter than the main portion of the glower, for then the points of contact with the wire will not during the operation of the lamp be as hot as the remainder of the glower, and therefore the wires themselves are less liable 15 to burn off. The paste or cement with which it is desirable to build up the ends may be of the same material as that used for forming the glower itself. I have obtained excellent 20 results by pulverizing portions of glowers which have been previously prepared and heated to high temperatures and mixing the 25 same with water, and, if desired, starch-paste may be added. Any suitable means for supporting the conducting-wires and securing 30 electrical connections therewith may be employed.

For the purpose of obtaining the preliminary or starting heating of the glower various different means may be employed. Usually it is desirable that the heat should be applied only during the starting process and then withdrawn, although in some cases it may be desired to continue the extraneous heat while the lamp itself is in operation. A very convenient starting-heater consists of a 45 coil of platinum wire or other conducting material which may be heated to a high temperature in the open air by the passage of electric currents without being melted. This wire is coiled or otherwise arranged in such 50 proximity to the glower that when heated by the passage of an electric current it will raise the glower to a sufficiently high temperature to cause it to acquire the necessary conducting capacity to permit sufficient current to 55 flow through it under the influence of the difference of potential of the circuit upon which it is to be used to carry it to a state of high incandescence and maintain it there. When the lamp has once been started, the 60 circuit through the heater may be interrupted manually or automatically, and, if it is desired, the heater may also be withdrawn from the immediate vicinity of the glower. Instead of imparting the starting-heat by the 65 agency of electric currents other extraneous sources of heat may be employed—as, for in-

stance, a gas-flame or the flame of a lamp, or even a match in some instances.

The temperature to which the glower must be brought in order to have sufficient conductivity to allow enough current to flow through it to maintain itself in that conductive condition varies somewhat with different materials and proportions. Some of the mixtures will produce a glower which when heated to 70 a conductive temperature will fall in resistance as rapidly under the influence of a constant difference of potential as to permit a current to flow which would be destructive to the glower. With such glowers means should 75 be employed for counteracting this effect and cause the glower to receive and consume only a predetermined amount of current, and therefore remain at a predetermined safe temperature. A convenient means for accomplishing 80 this result with such glowers consists in introducing in series with the glower a correctly-proportioned resistance, preferably having a high positive temperature coefficient, and therefore offering an increasing 85 opposition to the flow of the current with increments of current. Resistances composed of materials having little or no positive temperature corrections may, however, be used in certain cases. In constant-potential alternating- 90 current circuits reactive coils may be used in lieu of such resistance as above referred to. The expenditure of energy in such compensating devices when required may be very 95 low, as their effective resistance may be in 100 some cases as low as two per cent. or even less of the resistance offered by the glower when in operation if the lamps are used upon circuits having little or no variation in difference of potential—as, for instance, storage 105 battery circuits. When used upon circuits subject to wider variations, it may be desirable that this resistance should consume as much as five per cent. or even more. Upon alternating-current circuits where reactive 110 coils are used less than this will usually suffice.

The present application, which is a division of my application, Serial No. 679,081, dated April 28, 1898, relates more particularly to that feature of the original application which is concerned with the arrangement of the heating-body in an independent circuit with respect to the glower and also to the use of a transparent material as the support for the heater.

The present invention is illustrated in the accompanying drawings, in which—

Figure 1 is a diagram of an arrangement of circuits containing a heater and a glower in proximity to each other, these two elements 125 being in independent circuits; and Fig. 2 is an enlarged view of a glower.

Referring to the figures, C represents a suitable base for supporting the lamp. A suitable circuit-closing device D is provided, 130 by means of which the circuit from any suitable source G of electric current may be com-

pleted to the binding-posts $c' c^2$ of the lamp. The light-giving portion or glower A of the lamp is made in accordance with the description hereinbefore given. It is carried by two conductors $a' a^2$ of any suitable character, and these are connected with the terminals $c' c^2$ of the lamp. A bridge-piece a^3 may be employed for holding the conductors $a' a^2$ in their proper relative position. A heating or starting conductor B is shown in Fig. 1 as carried upon a glass or other transparent support H, and it incloses to a greater or less extent the glower A. Suitable supporting-clips f f are provided for receiving the ends 15 of the supports $a' a^2$, so that a glower may be readily replaced. The heater-support H is here mounted, through the medium of a standard c and bracket c^5 , so that both the support H and its heating-conductor B remain stationary. On the other hand, the glower A and the parts connected therewith are mounted upon a movable bracket K', connected with the core k of a solenoid K, forming part of the glower-circuit. The core 25 k is supported by a spring t, connected with a horizontal extension of the standard c. A downward movement of the core k within its solenoid will move the glower out from the inclosing support H. A rod r, passing through 30 an opening r', serves to guide the parts throughout their motion. It will be understood that in some cases it may not be desired to separate the heater and the glower from each other, in which case light from the glower will be transmitted through the transparent 35 heater-support. In this instance I have shown the heater as being supplied from a separate source G' of electricity instead of being in a branch circuit from the source G. The source 40 G and the source G' may either or both of them be sources of alternating or continuous current, as desired. In the heater-circuit I place a switch s, by means of which the circuit may be opened or closed. An automatic 45 circuit-interrupting device may be placed in the circuit of the heater, if desired. When the switches D and s are closed, the current passes through the heater B, raising the glower A to such a temperature as will render it sufficiently conductive to be traversed 50 by the current from the generator G. The solenoid K will then be energized, drawing down the core k against the force of the spring t and removing the glower A from within the 55 inclosing support H. The circuit through the heater may then be interrupted by means of the switch s, if desired. The interruption of the circuit through the glower automatically restores the parts to the positions shown 60 in Fig. 1.

By requirement of the Patent Office this application is divided out of my application, Serial No. 718,624, which was filed May 29, 1899, as a division of an earlier application, Serial No. 679,081, filed April 28, 1898. 65

I claim as my invention—

1. In an electric-lighting system, a source of electric current, a glower which is non-conductive when cold and requires to be heated to be rendered conductive, in circuit with the said source, and an electric heater in an independent circuit and located in proximity to the said glower. 70

2. In an electric-lighting system, a source of electric current, a glower which is non-conductive when cold and requires to be heated to be rendered conductive, in circuit with the said source, an electric heater in an independent circuit and located in proximity to the glower, and a switch in the heater-circuit for controlling the operation of the heater. 75

3. In an electric-lighting system, a source of electric current, a glower which is non-conductive when cold and requires to be heated to be rendered conductive, in circuit with the said source, an electric heater in an independent circuit and located in proximity to the said glower, and switches in the glower and heater circuits for controlling their operation. 80

4. In electric lamps, the combination with an incandescent body made of a material that is a non-conductor when cold and becomes a conductor when heated to a high temperature, of a resistance-conductor, a support of fireproof non-conducting and transparent material surrounding the said incandescent body, and means for heating said resistance-conductor by the passage of electric currents, substantially as and for the purpose described. 85

5. In electrical incandescent lamps, the combination with an incandescent body made of a material that is a non-conductor when cold and becomes a conductor when heated to a high temperature, of a wire resistance combined with a sleeve of fireproof non-conducting and transparent material such as glass surrounding the said incandescent body, and means for electrically heating said wire resistance, substantially as and for the purpose described. 90

Signed by me at Berlin this 27th of March, 1901.

WALTHER NERNST.
